UNITED STATES PATENT OFFICE.

CARL B. MOORE, OF GLENNS FERRY, IDAHO.

SOAP-RECEPTACLE.

1,257,095.

Specification of Letters Patent. Patented Feb. 19, 1918.

Application filed August 8, 1917. Serial No. 185,129.

To all whom it may concern:

Be it known that I, CARL B. MOORE, a citizen of the United States, residing at Glens Ferry, in the county of Elmore and State 5 of Idaho, have invented certain new and useful Improvements in Soap-Receptacles, of which the following is a specification.

This invention relates to a soap receptacle and the primary object is to provide an im- 10 proved receptacle for receiving a cake of soap, the receptacle being designed, to be attached to the edge of a wash basin, when desired, by employing the usual aperture provided in the marginal edge of wash 15 basins of the ordinary construction.

Another object of the invention is to pro- 20 vide a receptacle of this character divided into two compartments by a perforated par- tition whereby the soap may be permitted to drain through the partition to the lower- 25 most compartment.

Another object of the invention is to pro- 25 vide a soap receptacle of this character de- signed to permit the soap to be easily removed in a manner that will prevent the soap from slipping out of the fingers of the person de- 30 siring to use the same.

A further object of this invention is the provision of a soap receptacle which con- 30 sists of comparatively few parts and is sim- ple in construction, but durable and well adapted to withstand the rough usage to 35 which devices of this character are ordi- narily subjected.

For a full description of the invention and the advantages and merits thereof, ref- 40 erence is to be had to the following descrip- tion and the accompanying drawings, where- in is illustrated the preferred form of my invention, in which;

Figure 1 is a side elevation.

Fig. 2 is an end elevation.

Fig. 3 is an enlarged plan.

Fig. 4 is a central transverse vertical sec- 45 tion.

Referring to the drawing, wherein is illus- 50 trated the preferred form of my invention, and in which like numerals of refer- ence indicate corresponding parts through- out the several views, the main container 1 is preferably constructed from thin metal

or the like and is of substantially rectangu- 55 lar formation having end walls 2 and side walls 3 which may be of any desired depth. Pivotaly mounted within the container is a partition 4 mounted upon a hinge pin 5 near one side wall 3. A supporting flange 6 is fastened to the opposite side wall of the receptacle and the free edge of the parti- 60 tion normally rests on this flange as shown to advantage in Fig. 4 of the drawing. The partition 4 is perforated with a series of openings 7 to permit the water from the cake of soap to drain through the partition to the lowermost compartment. 65

To facilitate the extraction of the soap from the receptacle, I have provided each side wall 3 with a struck out portion forming a depression 8 and it will be apparent that the fingers of the user may thereby 70 gain a more effective hold on the cake of soap to remove it from the receptacle when the soap is wet and likely to slip from the fingers.

Fastened to one of the side walls 3, pref- 75 ferably in the center of one of the depres- sions 8, is a hook 9 which may be of any preferred construction and this hook is adapted to be inserted in the opening usually found in the marginal edge of a wash basin 80 so that the soap receptacle may thus be per- mitted to hang in the wash basin above the water contained therein so that the soap will be within convenient reach of the user. The hook 9, will also permit the soap recepta- 85 cle to be used in the edge of a wash tub or the like.

Foot bases 10 are fastened to the bottom of the receptacle and go as supports for the receptacle when the same is not sus- 90 pended by a hook.

From the foregoing it will be observed that a very simple and durable soap recep- 95 tacle has been provided, the details of which, embody the preferred form. I desire it to be understood, however, that slight changes in the minor details of construction may be made without departing from the spirit of the invention or the scope of the claim here- unto appended. 100

I claim—

A soap receptacle comprising a container

having its side walls, each provided with a depression, a partition hingedly mounted within the receptacle and held in spaced relation to the bottom of the receptacle, the 5 said depressions merging into the side walls of the receptacle at points slightly above the plane of the said partitions and a hook fixed to one of the side walls in the said de-

pressions and depending parallel to the said side wall on the exterior of the receptacle. 10

In testimony whereof I affix my signature in presence of two witnesses.

CARL B. MOORE.
